UNITED STATES PATENT OFFICE.

JOHN LUTHER BLAKE, OF MOBILE, ALABAMA, ASSIGNOR OF TWO-THIRDS TO
JOHN J. DUNN AND JAMES MONROE CLOUD, BOTH OF SAME PLACE.

SINGLETREE-IRON.

SPECIFICATION forming part of Letters Patent No. 394,445, dated December 11, 1888.

Application filed June 13, 1888. Serial No. 276,903. (No model.)

To all whom it may concern:

Be it known that I, JOHN LUTHER BLAKE, a citizen of the United States, and a resident of Mobile, in the county of Mobile and State 5 of Alabama, have invented certain new and useful Improvements in Singletree-Irons; and I do hereby declare that the following is a full, clear, and exact description of the invention, which will enable others skilled in the art to 10 which it appertains to make and use the same, reference being had to the accompanying drawings, which form a part of this specification, and in which—

Figure 1 is a perspective view of my improved singletree-iron, showing the same secured in operative position to the end of a singletree, and Fig. 2 is a transverse vertical sectional view of the same.

Similar letters of reference denote corresponding parts in both the figures.

My invention has relation to irons for singletrees; and it consists in the novel manner of removably securing the same to the said singletree, as will be hereinafter more fully 25 set forth.

In the accompanying drawings, the letter A denotes the singletree of the usual construction, and B indicates the iron formed with the eye C and with a transverse screw-threaded 30 perforation, D. This iron is slipped upon the end of the singletree, which is of less circumference than the iron, and a locking-plate, E, inserted in the space between the iron and the singletree. This plate is forced against the 35 singletree by means of a set-screw, F, screwed through the transverse aperture D, thus securely holding the iron in place. A seat is preferably formed in the locking-plate, as shown at F', for the inner end of the set-screw.

40 When the ends of the singletrees are rounded, as shown in the drawings, the iron is also

rounded and the locking-plate slightly curved, so as to conform with the singletree; but should the singletree be formed square the locking-plate and the iron will be constructed 45 accordingly.

The object and advantages of my invention will readily suggest themselves without requiring an extended description.

It will be seen that the iron can easily and 50 quickly be removed after having become worn and replaced with a new one, while the device is simple in construction, inexpensive to manufacture, and is exceedingly useful for the purpose for which it is designed.

Having thus described my invention, I claim and desire to secure by Letters Patent of the United States—

1. The combination of a singletree-iron of the usual construction and formed with a 60 transverse screw-threaded aperture, with a set-screw passing through said aperture, and a locking-plate.

2. The combination, with a singletree-iron of the usual construction and formed with a 65 transverse screw-threaded aperture, of a set-screw passing through said aperture, and a curved locking-plate.

3. The combination, with a singletree-iron of the usual construction and formed with a 70 transverse screw-threaded aperture, of a set-screw passing through said aperture, and a curved locking-plate formed with a seat or depression for the inner end of the screw.

In testimony that I claim the foregoing as 75 my own I have hereunto affixed my signature in presence of two witnesses.

JOHN LUTHER BLAKE.

Witnesses:

JAMES M. CLOUD,
JOHN F. WOODHULL.
